UNITED STATES PATENT OFFICE

1,931,926

FLOOR SCRAPER

David Johnson and George Larson, Rockford, Ill.

Application March 7, 1932. Serial No. 597,278

1 Claim. (Cl. 145—47)

Our present invention has reference to a manually operated scraping tool for floors and other surfaces which is characterized by simplicity in construction, cheapness to manufacture and reliability and efficiency in practical use.

To the attainment of the foregoing the invention consists in the improvement hereinafter described and definitely claimed.

In the drawing:

10 Figure 1 is a face view of the improvement.

Figure 2 is a sectional view approximately on the line 2—2 of Figure 1.

Figure 3 is a sectional view approximately on the line 3—3 of Figure 1.

15 The tool is constructed and is cast to provide a substantially rectangular member 1 whose upper end is centrally formed with a socket 2 for a handle 3. The second or outer end 4 of the member 1 is widened from its connection with the sides 20 5 thereof and this widened portion 4, from its outer edge is centrally formed with a continuous slot 6 that affords a pocket for the upper end of a scraper blade 7. The blade is clamped in the slot or bifurcation 6 by spaced bolts 8 that are 25 engaged by the usual nuts and between the heads of the bolts and the nuts there are preferably lock washers 9. The nuts and bolts compress the sides provided by the opening or bifurcation 6 in the end 4 toward each other so that the blade is 30 tightly clamped in the pocket provided therefor. The upper edge of the end 4, between the sides 5, is rounded, as at 10, and this rounded portion

may be engaged by the foot of the user of the tool, should the scraping operation be of such difficulty as to prevent the floor or like surface being properly scraped by the use of the handle 3.

The tool is operated in the usual manner, and 60 the central opening 11 provided by the tool not only affords a passage for the foot of the operator, should the scraping operation require additional pressure than is exerted by the hands of the operator on the handle 3, but the said opening 65 permits the passage of shavings therethrough.

It is believed that the simplicity of the construction and the advantages will be understood and appreciated so that further detailed description 70 will not be required.

Having described the invention, we claim:—

A floor scraper comprising a flat substantially rectangular member having one edge bifurcated, a scraping blade received by the bifurcated edge, a socketed element formed integrally with the 75 member and projecting beyond the opposite edge of said member from the bifurcated edge, a handle secured in the socketed element, means for securing the blade in the bifurcated edge of said member, said member having a rectangular 80 shaped opening and provided with a rounded wall adjacent the bifurcated edge to provide a rest for a person's foot when placed in the opening, said opening permitting shavings from the blade to 85 pass through said member.

DAVID JOHNSON.
GEORGE LARSON.
